CRUTCH

John D. Wheeler, Vancouver, Wash.

Application June 20, 1944, Serial No. 541,164

3 Claims. (Cl. 135—49)

The present invention relates to improvements in crutches and has for its general object the provision of an improved crutch which is more comfortable and convenient to use than the ordinary crutch.

Another object of the invention is to provide a crutch comprising upper and lower tubular sections, each section being adjustable as to length and adapted to be folded for a convenient placement in a position of rest or storage when not in use.

A further object of the invention is to provide a crutch of the above character including an arm rest that is rockably mounted so as to reduce to a minimum soreness under the arms of the user.

A still further object of the invention is to provide a crutch which is of light and durable construction and one which will afford a maximum of comfort to the user.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which

Figure 1 is a side elevation illustrating a crutch constructed in accordance with the present invention.

Figure 2 is a view in side elevation illustrating the crutch in folded position.

Figure 3 is a fragmentary perspective view of the upper section of the crutch with parts being shown in elevation.

Figure 4 is a detail sectional view illustrating the manner of joining the upper section with the lower section.

Figure 5 is a vertical sectional view taken substantially on line 5—5 of Figure 4.

Figure 6 is a sectional view similar to Figure 5 with the crutch in folded position.

Referring in detail to the drawing, the improved crutch is generally designated in the several views by the reference numeral 8 and comprises upper and lower sections generally designated by the reference numerals 9 and 10, respectively. The lower section 10 is of tubular formation and comprises the tubular members 11 and 12 arranged in telescoping relation with the member 12 adjustably held within the member

11 by means of a pin or the like 13. The member 11 has its upper portion curving outwardly as indicated at 14 and is then bent at right angles to form a hand grip 15. As more particularly shown in Figure 4 of the drawing, the hand grip 15 is of tubular formation and retains there-

5 in the upper section 9. The upper section 9 comprises tubular members 16 and 17 held in adjusted telescoping relation by means of a pin or the like 18. The lower end of the member 16 extends at right angles and is held within the hand grip 15 as indicated at 19. The end 19 is rotatably held within the hand grip 15 so that the crutch may be folded to the position shown in Figure 2. When in extended position, however, the end 19 is locked within the hand grip 15 by means of a pin 20 carried on the end of a leaf spring 21 riveted or otherwise secured as indicated at 22 to the hand grip 15. The pin 20 fits within an opening 23 formed in the end 19, a pair of such openings being provided so that said end 19 may be locked when the upper section is either extended or folded.

20 The upper end of the member 17 also extends at right angles and is substantially parallel to the end 19, said upper end being designated by the numeral 24. The end 24 is disposed within a channel 25 formed in the base 26 of the arm rest 27. The base 26 is pivotally connected to the end 24 by means of a pin or the like 28 whereby the arm rest 27 will rock on its pivot as indicated in dotted lines in Figure 1. The rocking of the arm rest 27 materially reduces or eliminates soreness under the arms of the user.

25 The improved crutch in accordance with the present invention is adjustable from either its upper or lower section. Adjustment of the upper section is occasioned by the necessity for decreasing or increasing the distance between the arm rest 27 and the hand grip 15 as some users may have longer or shorter arms than other users. Adjustment of the lower section is occasioned by the height of the user but when either section has been adjusted and locked by means of their respective pins, further movement is precluded. When desiring to fold the section 9 relative to the section 10, the pin 20 is retracted from the opening 23 and the former section swung downwardly to the position shown in Figure 2. The pin 20 is then replaced in its corresponding opening 23 for locking the sections in their folded position.

30 A rubber cap 29 is frictionally held on the lower end of the tubular member 12, said cap

being of the type conventionally employed for preventing slipping of the crutch when in use.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. A walking crutch comprising upper and lower sections, each section including telescoping tubular members, an arm rest carried by said upper section, a hand rest carried by said lower section, and means for foldably mounting said upper section relative to said lower section.

2. A walking crutch comprising upper and lower detachable sections, and an arm rest carried by said upper section, said lower section in-

cluding upper and lower tubular members, said lower member being telescopically held within said upper member, said upper member having its upper portion curved outwardly and bent inwardly at substantially right angles to the vertical plane to form a hand grip, the lower end of said upper section being pivotally mounted within said hand grip whereby said sections may be folded together.

10 3. A walking crutch comprising upper and lower detachable sections, said upper section including upper and lower tubular members, said lower member telescoping within said upper member, the free end of said upper member being bent at right angles to form a support for an arm rest, the free end of said lower member

15 being bent at right angles in a plane parallel to the bent end of said upper member, said lower section including upper and lower tubular members, said lower member thereof telescoping within said upper member thereof, and means for foldably mounting said upper section relative to said lower section.
